(57) **CLAIM**

The ornamental design for a hexagon shock absorber for a helmet as shown and described.

DESCRIPTION

FIG. 1 is a bottom view of a hexagon shock absorber for a helmet, showing our new design;

FIG. 2 is a top view thereof;

FIG. 3 is a front view thereof; and,

FIG. 4 is a side view thereof.

Broken lines are used to show the environment and form no part of the claimed design.
